WALL ANCHORING MEANS

Harry P. Homolya, Mexico, Mo., assignor to A. P. Green Fire Brick Company, Mexico, Mo., a corporation of Missouri

Application August 17, 1939, Serial No. 290,573

7 Claims. (Cl. 72—101)

My invention relates to wall anchoring means. The principal object of the invention is to devise a simple, effective and inexpensive means for anchoring a lining wall to the outer wall of a furnace or like structure so as to be steadied thereby and still be free to expand and contract independently of the outer wall. My invention consists principally in a metal member having at one end an eye adapted to receive a hook secured to the outer wall and having its other end enlarged to fit loosely in a socket that extends through the end of a refractory block adapted to be mounted in the lining wall, said socket having an opening through a side of the block and being of narrowest width in its middle portion. The invention also consists in the parts and in the combinations of parts hereinafter described and claimed.

In the accompanying drawing, which forms part of this specification and wherein like reference numerals refer to like parts wherever they occur,

Fig. 1 is a vertical sectional view of a portion of a double wall structure embodying my invention,

Fig. 2 is a vertical sectional view of a lining wall under construction, illustrating the placement of a refractory block,

Fig. 3 is an enlarged view of the anchoring means with adjacent portions of the wall structure shown in section,

Fig. 4 is a horizontal sectional view, on the line 4—4 of Fig. 3, of my anchoring device together with adjacent portions of the wall structure,

Fig. 5 is a plan view of my refractory anchoring block,

Fig. 6 is a vertical longitudinal section of said block on the line 6—6 of Fig. 5; and

Fig. 7 is an isometric projection of the metal member of my anchoring device.

As illustrated in Fig. 1, certain types of furnaces are built with an outer wall 1, which is usually made of brick, and an inner or lining wall 2 inside thereof and in contact therewith. The lining wall is usually built of refractory plastic material or refractory concrete or a mixture of high temperature cement and calcined grog or of refractory blocks. The lining wall is exposed to intense heat that causes expansion and contraction thereof and to transverse stresses that make it desirable to anchor the lining wall to the outer wall in such a manner as to be steadied against bulging or distortion due to excessive transverse or vertical movement and still leave

the lining wall free to expand and contract independently of the outer wall.

According to the present invention, my anchoring means comprises two main parts, namely, a refractory block 4 adapted to be mounted in the lining wall and a metal member 5 with one end 6 engaged in a socket 7 provided therefor in said refractory block and with an eye 8 in its other end 9 adapted to loosely engage a hook 10 provided therefor in the outer wall.

The refractory block is preferably pyramidal or wedge-shaped and its sides are preferably formed with ribs or depressions 11 so as to make interlocking engagement with the refractory concrete or plastic material in which the block is embedded when the wall is built. In practice, the concrete wall is built up and hammered, rammed or poured to a suitable height and then the refractory block or blocks are placed in position thereon with their small ends spaced from the outer wall and with their end portions covered with cardboard 21 to prevent the plastic concrete from coming in contact therewith. Then the pouring, ramming or hammering of the refractory material is resumed to raise the inner wall and embed the refractory blocks therein. In this way, the small end of each block projects into one of the recesses 3 thus formed in the outer face of the inner wall.

The small end portion 12 of the refractory block is provided with the socket 7 that opens through the small end of the block. The side walls 13 of this socket converge from each end of the socket to form a relatively narrow throat 14 connecting inner and outer triangular recesses 15, 16.

The metal member 5 is similar in shape to the socket 7; that is, the metal member has a relatively narrow middle portion 17 that fits loosely in the throat of the socket, and the sides 18 of its inner end diverge to fit loosely in the inner triangular portion 15 of said recess, and the outer end 19 of the metal member has diverging sides that fit loosely in the outer triangular portion 16 of the socket. This outer portion of the metal member has the eye 8 formed therein to loosely receive the vertically extending metal hook 10 that is mounted in the outer wall. As illustrated in the drawing, the converging faces of each side wall 13 of the socket 7 approach each other at an angle of the order of ninety degrees and the middle portion 14 that connects them is short and more or less rounded. The converging faces of the sides 18, 19 of the metal member also make an angle of the order of ninety degrees with each other and the neck portion between them is short.

This design affords a wide bearing at the inner end of the metal member in the socket 7 and enables the hook receiving opening 8 of the outer end to be made wide enough to permit considerable play between the metal member and the hook. It is noted also that along with these advantages is the fact that the metal member is short enough to permit the main and lining walls to be disposed close together.

As the inner end of the metal member 5 is wider than the throat of the socket 7, the socket is extended through the top of the refractory block so that the metal member can be entered into the socket through said opening in the top of the block. As shown at 20, the bottom wall of the socket terminates short of the side walls thereof so as to accommodate the metal hook of the outer wall.

In operation, the metal member is adequately supported by the refractory block in which it is mounted and it is also kept thereby in position for cooperation with the metal hook of the outer wall. Thus the inner wall is free to expand and contract vertically independently of the outer wall and still it is effectively steadied by the anchoring means against distortion due to excessive movement of the inner wall.

What I claim is:

1. A refractory wall-anchor block with converging sides, said block having a socket opening through its small end and through a side of said block, those side walls of the socket that are next to the open side of the socket converging from each end toward the middle to form a relatively narrow throat in the middle portion of said socket connecting inner and outer triangular portions.

2. A refractory wall-anchor block with converging sides, said block having a socket opening through its small end and through a side of said block, those side walls of the socket that are next to the open side of the socket converging from each end toward the middle to form a relatively narrow throat in the middle portion of said socket connecting inner and outer triangular portions, and the side of the block opposite the side that is open to said socket terminating short of the ends of the adjacent sides.

3. A refractory wall-anchor block with converging sides, said block having a socket opening through its small end and through a side of said block, said socket being narrowest in its middle portion, and the side of the block opposite the side that is open to said socket terminating short of the ends of the adjacent sides.

4. A wall anchoring device comprising a block

having a socket in one end and a metal member with a portion extending into and loosely mechanically interlocked with the socket portion of said block, said socket being open at the top and being narrower in its middle portion than at its ends and the metal member comprising a narrow middle portion that fits loosely in the middle portion of said socket, a wider end portion that fits loosely in the inner end portion of the socket and a relatively wide outer end portion that projects beyond the end of the block and has an eye extending vertically through it.

5. A wall anchoring device comprising a refractory block with converging sides having a socket extending through its small end, and a metal member with a portion extending into and loosely mechanically interlocked with the socket portion of said block, said socket being open at the top and being narrower in its middle portion than at its ends and the metal member comprising a narrow middle portion that fits loosely in the middle portion of said socket, a wider end portion that fits loosely in the inner end portion of the socket and a relatively wide outer end portion that has an eye extending vertically through it, the eye portion of said metal member extending outwardly beyond the end of the socket.

6. A wall anchoring device comprising a refractory block having a socket in one end and a metal member with a portion extending into and loosely mechanically interlocked with the socket portion of said block, said socket being open through one side of the block and being narrower in its middle portion than at its ends, and the metal member comprising a narrow middle portion that fits loosely in the middle portion of said socket, a wider end portion that fits loosely in the inner end portion of the socket and a relatively wide outer end portion that has an eye extending through it in position to receive a wall hook.

7. A wall tie for anchoring a lining wall to the outer wall of a furnace, said tie comprising a relatively short and narrow middle portion with concave sides and relatively wide end portions whose adjacent sides converge toward each other at an angle of the order of ninety degrees and merge into said concave sides of the middle portion, one of said end portions having a wide opening for a wall hook, whereby said wall tie is adapted to interlock loosely with a socket of like shape in an anchor tile and to interlock loosely with a wall hook.

HARRY P. HOMOLYA.
